Primary Examiner — Mojtaba Tehrani

(57) **CLAIM**

The ornamental design for a mosquito killer lamp, as shown and described.

DESCRIPTION

FIG. 1 is a top perspective view of the first embodiment of a mosquito killer lamp, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the second embodiment of a mosquito killer lamp, showing my new design;

FIG. 10 is a bottom perspective view thereof;

FIG. 11 is a front view thereof;

FIG. 12 is a rear view thereof;

FIG. 13 is a left side view thereof;

FIG. 14 is a right-side view thereof;

FIG. 15 is a top view thereof;

FIG. 16 is a bottom view thereof; and,

FIG. 17 is an enlarged detail view of the first embodiment's portion shown in FIG. 1.

The broken lines in the drawings illustrate unclaimed portions of the mosquito killer lamp, which form no part of the claimed design. The broken lines encircling portion of the claimed design shown in FIGS. 1 and 17 define unclaimed boundary of the enlarged isolated view only and form no part of the claimed design.

1 Claim, 17 Drawing Sheets
